JAMES F. SELL, OF CAMBRIDGE, ASSIGNOR TO CHARLES HOUGHTON, TRUSTEE, OF ROXBURY, MASSACHUSETTS.

Letters Patent No. 89,438, dated April 27, 1869.

IMPROVED PROCESS OF HARDENING TALC, STEATITE, &c.

The Schedule referred to in these Letters Patent and making part of the same.

To all whom it may concern:

Be it known that I, JAMES F. SELL, of Cambridge, in the county of Middlesex, and State of Massachusetts, have invented Improvements in the Treatment of Talc, Steatite, &c., to harden them; and I do hereby declare that the following is a description of my invention, sufficient to enable those skilled in the art to practise it.

Letters Patent of the United States, No. 71,919, were granted December 10, 1867, for the invention, by Henry Julius Smith, of a method of hardening talc, steatite, and other equivalent materials by heating them in a closed vessel, and in contact with carbon.

My invention is designed to effect the same purpose, and it consists in the following processes, viz:

First, in heating in a crucible talc, steatite, silicate of aluminum, silicate of magnesia, or silicate of aluminum and magnesia, or articles formed therefrom, in contact with common salt, (chloride of sodium,) either alone or combined with alum, sulphate of aluminum, and then removing the talc, &c., or the articles formed therefrom, while hot and immersing them in a bath of sulphuric acid.

Second, in heating the said materials, or either of them, or articles formed therefrom, in a crucible, and then removing and immersing them while hot in a bath

of sulphuric, nitric, muriatic, or other acid. After removal from the said bath, the material, whether treated by the first or second process, is washed with water, or with water containing an alkali to remove any adhering scale of the salt, or of the salt and alum, and any traces of the acid.

The salt, or the salt and alum, may be first fused in the crucible, or the talc, &c., and the salt, or the salt and alum may be placed together in the crucible, or the talc, &c., may be first heated and the salt, or the salt and alum may then be placed in the crucible.

The degree of heat applied to the tale, &c., whether salt, or salt and alum, is, or is not used prior to the immersion in the acid-bath, should be considerable but not up to a white heat.

I claim the treatment of talc, or equivalent matter, or articles formed therefrom, by first heating them, with or without contact of salt, or salt and alum, and then immersing the tale or its equivalent while hot, in a sulphuric or other acid bath, substantially as described.

JAMES F. SELL.

Witnesses:

FRANCIS GOULD,
C. WARREN BROWN.
